ENCASED PROJECTILE

Edgar William Brandt, Geneva, Switzerland, assignor to Anstalt für die Entwicklung von Erfindungen und gewerblichen Anwendungen Energa, a corporation of Vaduz (Principality of Liechtenstein)

Filed May 8, 1958, Ser. No. 733,900

Claims priority, application Switzerland May 13, 1957

3 Claims. (Cl. 102—38)

This invention relates to an encased projectile.

It is known that the propellant charge of projectiles with cartridges is generally contained loose in combustible bags (silk, Celluloid) inside a casing.

These arrangements tend, on ignition, to produce a random dispersal of the powder in the case and, in consequence of irregularities in combustion, a momentary lack of equilibrium in pressures and turbulent effects which have an unfavourable action on the internal ballistics of the projectile and which may produce, in the case of a projectile with empennage, a permanent deformation of the stabilising fins. Again, the direct action of hot gases on the more or less tapered face of the fins may give rise to partial combustion thereof, depending on the metal or alloy of which they are constructed.

The purpose of the present invention is to remedy the above-mentioned drawbacks and it has as its object a projectile which has an empennage and is enclosed inside a casing, the fins of the empennage extending to the rear beyond the end of the tail which supports the empennage, the said casing comprising in its base a powder chamber, the metal wall of which is provided with orifices and disposed facing the inner face of the fins of the empennage, and wherein the said orifices open between the fins only, the projectile and its case comprising means for securing them together in a determined angular position.

It follows that when the powder is ignited the rise in pressure is uniform on all parts of each fin and the jets of gas coming from the combustion chamber do not act directly on the face of the fins but on each side of these, which are thus protected from the blowpipe action to which they would otherwise be subjected on account of the high speed of combustion of the powder.

According to another characteristic of the invention, the powder chamber contains the whole of the propellant charge so that all the powder burns in the interior of the said chamber.

In the constructions previously known, only the igniting charge was housed in a cartridge-holder while the propellant charge was located outside the said cartridge-holder.

The previously mentioned chamber, on the other hand, has a constant volume, keeping the whole of the propellant charge at a constant density, the combustion then proceeding in a regular manner from one round to the next.

According to a particular embodiment of the invention the upper part of the powder chamber forms a seating for the support of the rear of the projectile.

This arrangement is conducive to the protection of the empennage fin tips, in that, should the projectile drop base downward, they do not run the risk of deformation through the projectile being forced into the case.

In a variant, the powder chamber, in conformity with the invention, is integrally joined by its base to a circular part constituting the base of the casing and screwed into the latter. In this way it is possible to remove the com-

2

plete propellant charge without the necessity of first taking the projectile out of its case.

Other advantages and special features of the invention will appear from the description which follows.

5 In the accompanying drawing, given solely by way of example,

Fig. 1 shows an elevation, with part broken away, of an empennaged projectile enclosed in a cartridge case;

10 Fig. 2 is a partial view, on a larger scale, of the enclosed projectile, the case and the powder chamber being in longitudinal section and

Fig. 3 is a partial transverse section taken on the line 3—3 in Fig. 1.

The projectile 1 comprises a rear part 2 at the end of 15 which there are three spread-out fins 3 which are articulated in a fin support 4. A case 5, preferably of brass or alloy of aluminum, in which the projectile 1 is encased, comprises at its base a steel chamber 6. The said chamber, which is in general of a shape like a truncated cone and of which the wall, orientated to face the inner face of the fins, is provided with orifices 7, contains a propellant charge 8. There is a polyethylene envelope (not shown) between the charge 8 and the perforated wall of the chamber 6. The firing of the charge 8 is 25 effected through a primer 9 ignited by percussion at the moment when the shot is fired.

The holes 7 are distributed in such a manner that none of them opens directly opposite the inner face of the fins 3; thus the chamber 6 comprises meridional zones 30 which are not perforated. It follows that the gases from the charge are ejected equally into each of the sections of the case marked out by the fins through the orifices 7 and that the dynamic pressure of the gases is uniformly distributed over every part of each fin.

35 The case 5 and the chamber 6 constitute between them a free annular space, to the bottom of which the empennage fins can extend, the entire propellant charge being contained in the said chamber.

The rear end 10 of the projectile can rest on the top 40 of the powder chamber 6 which thus assumes the character of a support for the projectile. This arrangement obviates all stress on the empennage as the result of the projectiles becoming forced into the casing during transport and handling or when the gun is being loaded.

45 According to a form of embodiment shown in the drawing the chamber 6 is secured by its base to a steel ring 11 constituting the base of the cartridge case and screwed into the latter. It follows from this that one can insert and remove the charge without separating the projectile from its case.

50 The projectile 1 is enclosed in the case 5 in such a way that the inner surface of each fin comes opposite the unperforated meridional zone of the chamber 6. To this end the case 5 is secured to the projectile 1, in a predetermined angular position, by the inward protuberance of the said case (Fig. 1) at three points 12, in which operation the case is pressed into corresponding recesses in the body of the projectile.

55 What I claim is:

60 1. A projectile to be fired from a rifled gun, a cartridge case within which said projectile is encased, said projectile comprising a body, a base at the rear of said body, said base carrying a forwardly pivoted folded fin assembly opening out rearwardly and formed with a plurality of fins, each of said fins extending, in folded position and over the greater part of its length, rearwardly of the base of the projectile, a powder chamber fixed to the rear end of the cartridge case and having perforations separated by a number of non-perforated longitudinal zones, cooperating means on the projectile and on the cartridge case for securing said parts together in a predetermined relation in which each of said fins is placed

opposite a non-perforated zone of said powder chamber.

2. A projectile to be fired from a rifled gun, a cartridge case within which said projectile is encased, said projectile comprising a body, a base at the rear of said body, said base carrying a forwardly pivoted folded fin assembly opening out rearwardly and formed with a plurality of fins, each of said fins extending, in folded position and over the greater part of its length, rearwardly of the base of the projectile, a powder chamber fixed to the rear end of the cartridge case and having perforations separated by a number of non-perforated longitudinal zones, cooperating means on the projectile and on the cartridge case for securing said parts together in a predetermined relation, in which each of said fins is placed opposite a non-perforated zone of said powder chamber, said means being constituted by one or more recesses made in the body of the projectile and one or more protuberances presented by the inner wall of said cartridge case, each protuberance being adapted to penetrate in a recess when each of said fins is placed opposite its corresponding non-perforated zone.

3. A projectile to be fired from a rifled gun, a cartridge case within which said projectile is encased, said

projectile comprising a body, a base at the rear of said body, said case carrying a forwardly pivoted folded fin assembly opening out rearwardly and formed with a plurality of fins, each of said fins extending, in folded position and over the greater part of its length, rearwardly of the base of the projectile, a powder chamber fixed to the rear end of the cartridge case and having perforations separated by a number of non-perforated longitudinal zones, cooperating means on the projectile and on the cartridge case for securing said parts together in a predetermined relation in which each of said fins is placed opposite a non-perforated zone of said powder chamber, the latter adapted to contain the entire propellant charge, so that all the powder burns in the interior of said chamber.
